UNITED STATES PATENT OFFICE.

GEORGE D. HUNTER, OF TERRE HAUTE, INDIANA.

SPARK-EXTINGUISHER.

SPECIFICATION forming part of Letters Patent No. 285,900, dated October 2, 1883.

Application filed August 7, 1883. (No model.)

To all whom it may concern:

Be it known that I, GEORGE D. HUNTER, a citizen of the United States, residing at Terre Haute, in the county Vigo and State of Indiana, have invented certain new and useful Improvements in Spark-Extinguishers, of which the following is a specification, reference being had therein to the accompanying drawings.

10 This invention relates to certain new and useful improvements in spark-extinguishers, and it is designed to be used either in connection with my spark-arrester, as described in my application for Letters Patent thereon filed even date herewith, or in connection with any other form of arrester, it being specially intended to be used with such as are located within the smoke-box of the locomotive; and it has for its objects, first, to provide means for continuously attracting and collecting sparks and other solid particles of combustion escaping from the fire-box into the smoke-box, and for transmitting them from the latter to a suitable receptacle; second, to provide means for receiving the sparks and other solid particles of combustion and the steam by which they are thus transmitted from the smoke-box; third, to provide means for allowing of the escape of the superfluous and unabsoed steam and of the gases that may follow and accompany it with the cinders into the receptacle.

With these ends in view my invention consists, essentially, in the employment of an exhaust-nozzle having a lateral opening, and of a pipe or conduit communicating with such nozzle and with the smoke-box, and leading into and discharging into a spark-receptacle; and it further consists in an improved smoke-box head or cap provided with steam-escaping conduits which communicate with the cinder-receptacle and with the open air or the stack.

In the accompanying drawings, forming a part of this specification, and on which like letters of reference indicate corresponding parts, Figure 1 represents a vertical sectional view taken longitudinally through the smoke-box of the locomotive, showing my improvements 45 in cross-section as applied thereto; Fig. 2, a vertical sectional view of the smoke-box head, taken on the line $x-x$ of Fig. 3; Fig. 3, a view in front elevation, showing one of the conduits in vertical section; Fig. 4, a view, partly in

side elevation and partly in vertical section, of the smoke-stack; Fig. 5, a detached perspective view of the T head or pipe and its elbow which conducts the cinders to the receptacle, and Fig. 6 a plan view of the cinder-receptacle detached.

The letter A indicates the smoke-box of the locomotive, the same being generally of the ordinary or any approved construction, in the lower side or bottom of which is mounted the exhaust-nozzle (or nozzles if more than one be used) A', the same being preferably a double-acting central discharge-nozzle, and provided with a partition, A², which terminates some distance below its mouth, whereby the discharge of the steam issues in a single volume. This nozzle has a branch, B, or an opening at one side, which communicates with the interior of the nozzle on each side of the partition, and which, if desired, may be provided with a thimble to contract the size of its mouth, as stated in my application filed even date herewith.

The letter B' indicates the pipe through which the cinders are discharged, the inner end of which extends within a short distance of the opening or branch B of the nozzle, and is provided with one or more slots or openings which communicate with the smoke-box. The forward end of this pipe has an elbow which terminates in a T-head, the mouth of which is flaring and provided with a perforated flange, B². This flange is bolted to the upper side of the cinder-receptacle, to be presently described, and the pipe passes through a suitable opening in the smoke-box head.

C indicates a cinder-receptacle, the same being constructed, preferably, of metal, and provided with one or more hand-holes, C', having covers. This receptacle has a door at its bottom, by which the cinders may be discharged, the said door, by preference, being operated from the cab of the engine through suitable connections. It is secured to the frame C², and is located just forward of the smoke-box.

The letter D refers to the smoke-box head, the same being constructed, by preference, of cast-iron, and secured to the smoke-box through the instrumentality of the ring D', which is fastened to the forward end of its shell. This head D is cast or otherwise provided with curved conduits D², which are on its forward side, and which partially encircle the door.

opening. The upper ends of these conduits unite, while the lower ends each communicate with the cinder-receptacle C through the openings *a*, flanges being formed around the terminals of the conduits, in order that they may be bolted, if desired, to the said receptacle. By preference the part of the head which forms the outer walls of the conduit extends across the space between their lower ends, as seen in Fig. 3, through which portion an aperture is made for the passage of the pipe D'. I provide the head with the usual door, E, which may be provided with the ordinary devices for keeping it in a closed position.

The letter E' refers to the smoke-stack, which in this instance is mounted upon the smoke-box in the manner described in my contemporaneous application, and which is double walled, as seen at E² and F. The wall is shorter than the wall E², and is provided with an ornamental cap, F', the opening at the top of which is slightly larger in diameter than the inner wall, E², which latter also extends slightly above the cap, for a purpose which will presently appear. The outer wall is further provided near its base with an aperture, around which is fitted and secured the upper end of the communicating pipe of leg F², the lower end of which fits over the upper terminals of the conduits, and is connected to the head D. In some instances, however, I contemplate allowing the conduits to discharge into the open air, and may provide them with a pipe independent of the stack, which may extend to any desired height.

It will be understood that I contemplate providing the smoke-box, or in some instances the lower end of the stack, with a suitable diaphragm or other means which will act to cut off the upward escape of the cinders or other solid particles of combustion which pass from the fire-box through the flues, and yet allow the escape of the smoke and gases.

The nozzle is to be extended upwardly to any desired height. As the cinders and sparks issue with the smoke and gases from the flues, they, on being prevented from going up the stack, will gravitate and collect, to a certain extent, in the lower part of the smoke-box, from which place they are attracted and drawn into the pipe B' through the broken joint between it and the nozzle, and through its slots by the action of the escaping exhaust through the branch or opening B. From the pipe B' they are discharged, together with the steam, which draws them into and forces them through the said pipe, into the cinder-receptacle C. I have ascertained that the sparks are thus entirely extinguished, and that the steam partially condenses, the condensation collecting in the said receptacle. The superfluous steam issues through the openings *a* into conduits D², and thence either into the open air or into the annular space between the walls of the stack, and from it finally through an opening in the top of the ornamental cap. The inner wall of the stack

extends above this cap, so as to prevent the smoke and dust from collecting in the said cap.

In some instances I may not use the inner solid section of the pipe B', as I have ascertained by actual trial that it is not positively necessary to the successful operation of the extinguisher; but I prefer to use the said section of pipe because it acts to more thoroughly clear the smoke-box of cinders and sparks.

Having thus fully described my invention, what I claim as new, and desire to secure by Letters Patent, is—

1. In a spark-extinguisher, the combination, with the exhaust-nozzle having a dividing-partition and the lateral opening communicating therewith on each side of said partition, of the cinder-receptacle, the pipe communicating with it and the smoke-box, provided with slots and extending near to said opening, whereby exhaust-steam issues into it and the sparks are drawn therein through its end and through the slots, substantially as described.

2. In a spark-extinguisher, the combination, with the exhaust-nozzle having a lateral opening, the cinder-receptacle, and the slotted pipe communicating with it and the smoke-box, of the smoke-box head having conduits which communicate with said receptacle and with the smoke-stack, substantially as described.

3. In a spark-extinguisher, the combination, with the exhaust-nozzle having a lateral opening and the cinder-receptacle communicating with the smoke-box, of the smoke-box head having conduits and the double-walled smoke-stack communicating with said receptacle through the conduits, substantially as described.

4. In a spark-extinguisher, the combination, with the cinder-receptacle adapted to receive the cinders from the smoke-box by the action of the exhaust-steam, of the smoke-box head having the conduits, the double-walled smoke-stack having an inner wall extending above the outer wall, and the pipe for connecting the conduits and the stack, substantially as described.

5. In a spark-extinguisher, the combination of the smoke-box with the head thereof, provided with curved conduits adapted to receive superfluous steam from the cinder-receptacle and to discharge the same into the stack, substantially as described.

6. In a spark-extinguisher, the smoke-box head provided with conduits and a door-opening, substantially as described.

7. In a spark-extinguisher, the smoke-box head provided with conduits, substantially as described.

In testimony whereof I affix my signature in presence of two witnesses.

GEORGE D. HUNTER.

H. J. ENNIS.

Correction in Letters Patent No. 285,900.

It is hereby certified that in Letters Patent No. 285,900, granted October 2, 1883, upon the application of George D. Hunter, of Terre Haute, Indiana, for an improvement in "Spark-Extinguishers," an error appears requiring correction, as follows: in line 11, page 2 of the printed specification, the reference letter "D'" should read *B'*; and that the patent should be read with this correction therein to make it conform to the record of the case in the Patent Office.

Signed, countersigned, and sealed this 13th day of November, A. D. 1883.
